UNITED STATES PATENT OFFICE.

OSCAR A. SMITH, OF CLEVELAND, OHIO, ASSIGNOR TO THE NATIONAL-ACME MANUFACTURING COMPANY, OF CLEVELAND, OHIO, A CORPORATION OF OHIO.

METAL-WORKING MACHINE.

1,104,147.

Specification of Letters Patent.

Patented July 21, 1914.

Application filed May 23, 1911. Serial No. 629,020.

To all whom it may concern:

Be it known that I, OSCAR A. SMITH, a citizen of the United States, residing at Cleveland, in the county of Cuyahoga and 5 State of Ohio, have invented certain new and useful Improvements in Metal-Working Machines, of which the following is a specification.

This invention relates to metal working 10 machines of that class known as automatic or multiple spindle screw machines, the object of the invention being to provide a machine of this class having improved means for revolving or indexing the work spindle 15 turret at a rapid or accelerated speed, whereby the production of the machine is materially increased.

A further object of the invention is the provision, in a multiple spindle screw machine, of a two-part driving or cam shaft, said shafts carrying mechanism whereby the rotation of one will be controlled by the other and whereby one shaft may remain idle during a predetermined period while 25 the other is rotating and will have increased speed as compared with the other during another predetermined period, thereby to index the turret rapidly.

In the drawings accompanying and forming part of this specification, Figure 1 is a top plan view of a machine of the class described having this improved driving means; Fig. 2 is a side elevation thereof with parts in section; Fig. 3 is a perspective view of the 35 revoluble turret and the driving mechanism for indexing the same; Fig. 4 is an end view of the machine looking from right to left in Fig. 1; and Figs. 5 and 6 illustrate details of a part of the mechanism for imparting rotation from one shaft to the other thereby to control the indexing of the turret.

Similar characters of reference indicate corresponding parts throughout the figures of the drawings.

45 The present improved machine, in the embodiment shown, comprises a suitable supporting frame or bed 2 having mounted thereon a turret casing 3, within which is located a rotary work spindle turret or cylinder 4, which may carry any desired number of work spindles 5, four of which are shown herein. Each of these work spindles is provided with the usual clutch 6 and a gear 7 in mesh with a gear 8 located on the end of

the work spindle driving shaft 9, which 55 passes through and is rotatable within the turret 4 and by means of which rotary movement is imparted to the rotary work spindles mounted within the turret. This shaft passes through the usual sliding tool head 60 10 and may be supported at its opposite end by a suitable bearing in a bracket 11 secured to the bed of the machine. This shaft 9 may be driven in any suitable manner, but a conventional form of driving means is shown 65 herein, consisting of a bevel gear 12 fixed to the end of the shaft and in mesh with a bevel gear 13 fixed to a transverse shaft 14 carrying at its end a gear 15 in mesh with another gear 16 mounted on a sleeve 17 suitably supported on a stud 17', and on the end of which sleeve 17 is a sprocket gear 18 for the reception of a sprocket chain 19 running to a sprocket gear 20 carried on the end of a worm shaft 21, which latter shaft constitutes the means for rotating the turret driving or cam shaft, this worm shaft being suitably supported on the base of the machine. Of course it will be understood that any desired means for driving the work spindle 80 shaft, and thereby the work spindles, may be used.

In mesh with the worm of the worm shaft 21 is a worm wheel 22 fixed to a tubular shaft 23 suitably supported on the bed of 85 the machine, and on the end of the worm shaft 21 is located a driving pulley 24 connected with any suitable source of power, as for instance by means of a belt. This tubular shaft 23 will in practice carry a cam 90 drum 25, which carries the usual cams 26 for sliding the tool head toward and from the turret and will also carry such other cams as may be necessary for actuating certain parts of the mechanism, as for instance 95 the cutting off tools. Extending through this tubular shaft 23 is a shaft 27, the rear end of which is suitably supported or housed in the bed of the machine and carries the usual cam drum 28 for operating the clutches 100 in the well known manner. This shaft 27 also carries a fan gear 29 in mesh with a gear 30 fixed to the rotary turret and by means of which the turret is indexed at predetermined intervals. This shaft 27, therefore, intermediate the indexing of the turret, is intended to remain stationary while the tubular shaft 23 is intended to constantly 105

rotate through the medium of the worm shaft 21 and the worm wheel 22 fixed to this tubular shaft 23.

For rotating the shaft 27 at the proper time suitable mechanism is provided. In the present instance this consists of a sprocket wheel 31 fixed to the end of the worm shaft 21 for the reception of a sprocket chain 32 running to a sprocket wheel 33 fixed on the end of another worm shaft 34, the worm 35 of which is in mesh with a worm wheel 36 loosely mounted on the tubular shaft 23. To this worm wheel 36 is secured a disk 37 carrying a pawl 38 and spring 39, and which disk therefore may be hereinafter designated as a pawl disk. The ratio of the two sprockets 31 and 33 is three to one in the present embodiment of the machine, so that the worm wheel 36, which as stated is loose upon the tubular shaft, is driven uninterruptedly three times as fast as the worm wheel 22, which is fixed to the tubular shaft. Located on that end of the shaft 27 nearest the worm wheel 36 is a clutch disk 39 having a plurality of recesses or notches 40 therein, shown herein as three in number, this disk being keyed to the shaft 27 for rotation therewith, the recesses 40 being located to receive the pawl 38 at certain periods. From this it will be observed that when the pawl extends into any one of the recesses 40 motion will be imparted from the worm wheel 36 loose upon the tubular shaft 23, and the pawl disk 37, to the clutch disk 39 keyed to the shaft 27, whereupon the latter will be rotated to bring the fan gear 29 into engagement with the teeth of the gear 30 and so rotate or index the turret so long as the fan gear is in mesh with such teeth, and that, as the ratio of the sprockets 31 and 33 is three to one, it follows that the shaft 27 will be rotated at the intervals referred to three times as fast as the tubular shaft 23, thus rapidly indexing the turret and thereby saving considerable loss of time in the operation of the machine and consequently increasing the output or product of such machine. Keyed to the tubular shaft 23 is a cam disk 41 having three camming or tripping portions 42 for successively engaging the pawl 38 and shifting it against the action of its spring out of the recesses 40 of the clutch disk 39, at which time further rotation of the shaft 27 ceases.

From the foregoing it will be observed that when power is applied to the driving pulley 24 on the worm shaft 21 this worm drives the main drive worm wheel 22 keyed to the tubular shaft 23, driving the pawl releasing cam 41 at the same speed, while at the same time it rotates the sprockets 31 and 33 and thereby the worm wheel 36 and the pawl disk 37 in the manner hereinbefore stated, so that when the pawl 38 enters a notch of the clutch disk 39, which is as herein-

before stated keyed to the shaft 27 this shaft is rotated at a speed of three to one of the tubular shaft 23 and continues to run at that speed until the pawl is brought into engagement with one of the cam faces 42 of the cam 41, whereupon the pawl is disengaged from the clutch disk 39 thereby allowing the shaft 27 to stop until such pawl again engages a succeeding notch, and so on. These successive operations are performed three times in one complete revolution of the shaft. At the end of one complete revolution of this tubular shaft the shaft 27 will have made one complete rotation, although the speed thereof during such intermittent rotation is, as hereinbefore stated, considerably greater than the speed of the tubular shaft. Thus it will be observed that at three distinct periods the shaft 27 is running three to one times as fast as the tubular shaft.

In practice the cams of the cam drum 25 may be so formed as to give the desired slow movement to the tool head during the cutting or working operations of the tools and intermediate thereof the desired rapid movement to retard and return the tool head into its working position.

From the foregoing it will be observed that the tubular shaft 23 is rotated at a uniform speed continuously, while the shaft 27 is intermittently rotated, but at considerably greater speed than the tubular shaft 23, so that the turret is rapidly indexed, and much more so than if the tubular shaft constituted the means for imparting rotary movement to the turret.

I claim as my invention:

1. In a machine of the class described, the combination with a rotary turret and a reciprocating tool slide, of means for indexing the turret at a rapid speed and accelerating the speed of the tool slide and comprising a pair of shafts one extending into the other, the latter continuously rotatable and carrying means for actuating the tool slide and the former intermittently rotatable but at an increased speed as compared with the speed of the continuously rotatable shaft and carrying means for rotating the turret, means for rotating said shafts and comprising two sets of worm and worm wheel gearing, and means intermittently connecting one of said sets of worm wheel gearing with the intermittently rotatable shaft.

2. In a machine of the class described, the combination with a rotary turret and a reciprocating tool slide, of means for indexing the turret at a rapid speed and accelerating the speed of the tool slide and comprising a pair of shafts one continuously rotatable and carrying means for actuating said tool slide and the other intermittently rotatable but at an increased speed as compared with the speed of the continuously rotatable

- shaft and carrying means for rotating the turret, means for rotating the continuously rotatable shaft and rotating the intermittently rotatable shaft from the continuously rotatable shaft and comprising two sets of worm and worm wheel gearing, and means intermittently connecting one of said sets of worm wheel gearing with the intermittently rotatable shaft.
5. A machine of the class described having a pair of cam bearing shafts, and means for causing one of said shafts to be rotated intermittently by but at a higher speed than the other of said shafts and comprising two sets of worm and worm wheel gearing and means intermittently connecting one of said sets of worm wheel gearing with the intermittently rotatable shaft.
10. 3. A machine of the class described having a pair of cam bearing shafts, and means for causing one of said shafts to be rotated intermittently by but at a higher speed than the other of said shafts and comprising two sets of worm and worm wheel gearing and means intermittently connecting one of said sets of worm wheel gearing with the intermittently rotatable shaft.
15. 4. A machine of the class described having a pair of cam bearing shafts one extending into the other, and means connecting said shafts for causing the inner to be intermittently rotated by but at a higher speed than the outer shaft, the inner shaft carrying turret rotating means and the outer shaft tool slide actuating means.
20. 5. In a machine of the class described, the combination with a rotary turret and a reciprocatory tool slide, of a pair of shafts one within the other, the outer shaft carrying means for actuating the tool slide and the inner shaft carrying means for rotating the turret, and means for connecting said shafts and causing one of said shafts to be
25. rotated intermittently by but at a higher speed than the other and comprising a notched member fixed to one of said shafts, a pawl cooperating with said notched member, and a cam fixed to the other shaft for interrupting the connection between said pawl and notched member at predetermined times.
30. 6. In a machine of the class described, the combination with a rotary turret and a reciprocatory tool slide, of a pair of shafts, one within the other, the outer shaft carrying means for actuating the tool slide and the inner shaft carrying means for rotating the turret, and means for connecting said shafts and causing one of said shafts to be rotated intermittently by but at a higher speed than the other and comprising a notched member fixed to one of said shafts, a rotatable pawl loosely mounted upon the other shaft and
35. 65. cooperating with said notched member, a cam fixed to said last shaft for interrupting the connection between said pawl and notched member at predetermined times, and means for continuously rotating said pawl and notched member relatively to the other.
7. In a machine of the class described, the combination with a rotary turret and a reciprocatory tool slide, of a pair of shafts one within the other, the outer shaft carrying
40. 75. continuously rotatable and carrying means for actuating the tool slide and the inner shaft intermittently rotatable but at a higher speed and carrying means for rotating the turret, means for rotating the continuously rotatable shaft and comprising a worm and worm wheel, the latter fixed to said continuously rotatable shaft, means for rotating the intermittently rotatable shaft and likewise comprising a worm and worm wheel, the latter loose upon said continuously rotatable shaft, and means intermittently connecting one of said sets of worm wheel gearing with the intermittently rotatable shaft.
8. In a machine of the class described, the combination of a rotary turret having a plurality of work carrying spindles, and means for indexing the turret at a rapid speed and comprising a pair of shafts one continuously rotatable and the other intermittently rotatable but at an increased speed as compared with the speed of the continuously rotatable shaft, means for rotating the continuously rotatable shaft and comprising a worm and worm wheel, the latter fixed to said continuously rotatable shaft, means for rotating the intermittently rotatable shaft and likewise comprising a worm and worm wheel, the latter loose upon said continuously rotatable shaft, means for imparting motion from one worm to the other, and means connected with said last worm wheel for imparting motion therefrom to said intermittently rotatable shaft.
9. In a machine of the class described, the combination of a rotary turret having a plurality of work carrying spindles, and means for indexing the turret at a rapid speed and comprising a pair of shafts one continuously rotatable and the other intermittently rotatable but at an increased speed as compared with the speed of the continuously rotatable shaft, means for rotating the continuously rotatable shaft and comprising a worm and worm wheel, the latter fixed to said continuously rotatable shaft, means for rotating the intermittently rotatable shaft and likewise comprising a worm and worm wheel, the latter loose upon said continuously rotatable shaft, means for imparting motion from one worm to the other, and means connected with said last worm wheel for imparting motion therefrom to said intermittently rotatable shaft.
10. In a machine of the class described, the combination with a rotary turret and a reciprocatory tool slide, of a pair of shafts one within the other, the outer shaft carrying
95. 100. 105. 110. 115. 120. 125. 130.

- the inner shaft carrying means for rotating the turret, means for connecting said shafts and causing one of said shafts to be rotated intermittently but at a higher speed than the other and comprising a pair of coöperating members, means for rotating one of said members continuously, and a rotatable cam for breaking connection between said members at predetermined periods.
19. 11. In a machine of the class described, the combination with a rotary turret and a reciprocating tool slide, of a pair of shafts one within the other, the outer shaft carrying means for actuating the tool slide and the inner shaft carrying means for rotating the turret, and means for connecting said shafts and causing one of said shafts to be rotated intermittently but at a higher speed than the other and comprising a pair of coöperating members, one a pawl and the other a notched disk, means for rotating said pawl continuously, and a rotatable cam for breaking connection between said members at predetermined periods.
25. 12. A machine of the class described having a pair of shafts one within the other, means for driving the outer of said shafts continuously, means for connecting said shafts and causing the inner shaft to be rotated intermittently but at a higher speed than the outer and comprising two sets of similar gearing and a pair of coöperating members, one a pawl and the other a notched disk, and a cam for breaking connection between said members at predetermined periods.
30. 13. A machine of the class described having a pair of shafts, one continuously rotatable and the other intermittently rotatable but at a higher speed than the other, means for rotating the continuously rotatable shaft and for rotating the intermittently rotatable shaft and comprising two sets of worm and worm wheel gearing, the worm wheel of both sets carried by one of said shafts, and means intermittently connecting one of said sets of worm wheel gearing with the intermittently rotatable shaft.
35. 14. A machine of the class described having a pair of shafts, one continuously rotatable and the other intermittently rotatable but at a higher speed than the other, means for rotating the continuously rotatable shaft and for rotating the intermittently rotatable shaft and comprising two sets of worm and worm wheel gearing, the worm wheel of both sets carried by the continuously rotatable shaft one loosely mounted relatively thereto, and means intermittently connecting one of said sets of worm wheel gearing with the intermittently rotatable shaft.
40. 15. A machine of the class described having a pair of shafts, one within the other, the outer shaft being continuously rotatable and the inner shaft intermittently rotatable but at a higher speed than the outer, driving means for rotating the continuously rotatable shaft, means also connected with said driving means for imparting such intermittent rotation at a higher speed to the intermittently rotatable shaft, and means for interrupting the connection between the shafts whereby one of said shafts will remain idle at certain periods.
45. 16. In a machine of the class described, the combination of a rotary turret having a plurality of work carrying spindles, and means for indexing the turret at a rapid speed and comprising a pair of shafts one extending into the other, one continuously rotatable and the other intermittently rotatable but at an increased speed as compared with the speed of the continuously rotatable shaft, means for driving the continuously rotatable shaft and means operated by said driving means for intermittently driving the intermittently rotatable shaft, both of said driving means comprising a worm and worm wheel connected by gearing having different speeds, one of the driving worm wheels being loosely mounted upon the continuously rotatable shaft.
50. 17. In a machine of the class described the combination of a rotary turret having a plurality of work carrying spindles, and means for indexing the turret at a rapid speed and comprising a pair of shafts one extending into the other, one continuously rotatable and the other intermittently rotatable but at an increased speed as compared with the speed of the continuously rotatable shaft, means for driving the continuously rotatable shaft and means operated by said driving means for intermittently driving the intermittently rotatable shaft, both of said driving means comprising a worm and worm wheel connected by gearing having different speeds, one of the driving worm wheels being loosely mounted upon the continuously rotatable shaft, a spring actuated pawl connected therewith, a notched disk fixed to the intermittently rotatable shaft for the reception of said pawl, and a cam fixed to the continuously rotatable shaft for interrupting the connection between the pawl and the notched disk.
55. 18. In a machine of the class described, the combination of a rotary turret having a plurality of work carrying spindles, means for indexing the turret at a rapid speed and comprising a pair of shafts one extending into the other, one continuously rotatable and the other intermittently rotatable but at an increased speed as compared with the speed of the continuously rotatable shaft, means for driving the continuously rotatable shaft and means operated by said driving means for intermittently driving the intermittently rotatable shaft, both of said driving means comprising a worm and worm

wheel connected by gearing having different speeds, one of the driving worm wheels being loosely mounted upon the continuously rotatable shaft, a spring actuated pawl connected therewith, a notched disk fixed to the intermittently rotatable shaft for the reception of said pawl and a cam fixed to the continuously rotatable shaft for interrupting the connection between the pawl and the notched disk, a sliding tool carrier movable toward and from the turret, and cam mechanism mounted on the continuously rotatable shaft for reciprocating said sliding tool carrier.

19. In a machine of the class described, the combination of a rotary turret having a plurality of work carrying spindles, and means for indexing the turret at a rapid speed and comprising a pair of shafts, one a tubular shaft continuously rotatable and the other extending into said tubular shaft and intermittently rotatable and carrying means for rotating the turret, means for rotating said tubular shaft continuously and means for rotating at an accelerated speed said intermittently rotatable shaft from said tubular shaft.

20. In a machine of the class described, the combination of a rotary turret having a plurality of work carrying spindles, a reciprocating tool slide, means for indexing the turret at a rapid speed and comprising a pair of shafts, one a tubular shaft continuously rotatable and carrying means for actuating the tool slide and the other extending into said tubular shaft and intermittently rotatable, means for rotating said tubular shaft continuously and means for rotating at an accelerated speed said intermittently rotatable shaft from said tubular shaft, each of said shaft rotating means comprising a worm and worm wheel, one fixed to the tubular shaft and the other loosely mounted thereon, gearing for imparting motion from one worm to the other and having different speeds, means driven by said loosely mounted worm wheel for driving the intermittently rotatable shaft and means carried by the tubular shaft for interrupting the driving of said intermittently rotatable shaft.

21. In a machine of the class described, the combination of a rotary turret having a plurality of work carrying spindles, a reciprocating tool slide, means for indexing the turret at a rapid speed and comprising a pair of shafts, one a tubular shaft continuously rotatable and carrying means for actuating the tool slide and the other extending into said tubular shaft and intermittently rotatable, means for rotating said tubular shaft continuously and means for rotating at an accelerated speed said intermittently rotatable shaft from said tubular shaft, each of said shaft rotating means comprising a worm and worm wheel, one

fixed to the tubular shaft and the other loosely mounted thereon, gearing for imparting motion from one worm to the other and having different speeds, means driven by said loosely mounted worm wheel for driving the intermittently rotatable shaft, means carried by the tubular shaft for interrupting the driving of said intermittently rotatable shaft, gearing carried by said turret, and a fan gear carried by said intermittently rotatable shaft and adapted to mesh with the turret gearing at intervals.

22. In a machine of the class described, the combination of a rotary turret having a plurality of work carrying spindles, means for indexing the turret at a rapid speed and comprising a pair of shafts, one a tubular shaft continuously rotatable and the other extending into said tubular shaft and intermittently rotatable for indexing the turret, means for rotating said tubular shaft continuously and means for rotating said intermittently rotatable shaft from said tubular shaft, a sliding tool carrier shiftable toward and from the turret, and cam mechanism carried by the tubular shaft for reciprocating said tool carrier.

23. In a machine of the class described, the combination of a rotary turret having a plurality of work carrying spindles, means for indexing the turret at a rapid speed and comprising a pair of shafts, one a tubular shaft continuously rotatable and the other extending into said tubular shaft and intermittently rotatable for indexing the turret, means for rotating said tubular shaft continuously and means for rotating said intermittently rotatable shaft from said tubular shaft, each of said shaft rotating means comprising a worm and worm wheel, one fixed to the tubular shaft and the other loosely mounted thereon, gearing for imparting motion from one worm to the other and having different speeds, means driven by said loosely mounted worm wheel for driving the intermittently rotatable shaft and means carried by the tubular shaft for interrupting the driving of said intermittently rotatable shaft, a sliding tool carrier shiftable toward and from the turret, and cam mechanism carried by the tubular shaft for reciprocating said tool carrier.

24. In a machine of the class described, the combination of a rotary turret having a plurality of work carrying spindles, means for indexing the turret at a rapid speed and comprising a pair of shafts, one a tubular shaft continuously rotatable and the other extending into said tubular shaft and intermittently rotatable, means for rotating said tubular shaft continuously and means for rotating said intermittently rotatable shaft from said tubular shaft, each of said shaft rotating means comprising a worm and worm wheel, one fixed to the tubular shaft

and the other loosely mounted thereon, gearing for imparting motion from one worm to the other and having different speeds, means driven by said loosely mounted worm wheel 5 for driving the intermittently rotatable shaft, means carried by the tubular shaft for interrupting the driving of said intermittently rotatable shaft, gearing carried by said turret and a fan gear carried by said 10 intermittently rotatable shaft and adapted to mesh with the turret gearing at intervals, a sliding tool carrier shiftable toward and from the turret, and cam mechanism carried by the tubular shaft for reciprocating said 15 tool carrier.

25. In a machine of the class described, the combination of a rotary turret having a plurality of work carrying spindles and gearing, means for indexing the turret at a 20 rapid speed and comprising a pair of shafts, one a tubular shaft and continuously rotatable and the other an intermittently rotatable shaft extending into said tubular shaft, a fan gear fixed to said continuously rotatable shaft and adapted to mesh at intervals 25 with the gearing of the turret, means for driving said tubular shaft and comprising a worm wheel fixed thereto and a worm shaft, means for driving the intermittently rotatable shaft from the tubular shaft and comprising a worm wheel loosely mounted on 30 said tubular shaft and a worm driven from said first worm at an increased speed as compared with the speed of said first 35 worm, a notched disk fixed to said intermittently rotatable shaft, a spring actuated pawl connected to and rotatable with said loosely mounted worm wheel and adapted to cooperate with the notches of said disk 40 at intervals, a cam fixed to said tubular shaft and adapted to release the pawl from said notched disk at intervals, a sliding tool car-

rier movable toward and from the turret, and cam mechanism rotatable with the tubular shaft for reciprocating the tool carrier. 45

26. In a machine of the class described, the combination of a rotary turret having a plurality of work carrying spindles, a sliding tool carrier, a rotatable shaft, means for driving it at a constant speed, means carried thereby for reciprocating the tool carrier, and means connected with and driven by the shaft driving means for rapidly indexing the turret. 50

27. In a machine of the class described, the combination of a rotary turret having a plurality of work carrying spindles, a sliding tool carrier, a rotatable shaft, means carried thereby for reciprocating said tool carrier, means for driving said shaft at a constant speed and comprising a pair of gear members, and means for indexing the turret at a rapid speed and receiving its power 60 from one of said gear members.

28. In a machine of the class described, the combination of a rotary turret having a plurality of work carrying spindles, a sliding tool carrier, a rotatable shaft, means carried thereby for reciprocating said tool carrier, means for driving said shaft at a constant speed and comprising a worm and a worm wheel fixed to said shaft, and means for indexing the turret at a rapid speed and comprising a shaft and means connected 70 with the driving means for said constant speed shaft for rotating said turret indexing shaft. 75

Signed at Cleveland, Ohio, this 15th day of May, 1911.
